JACK FOR SHOE-MACHINES.

1,104,016.

Specification of Letters Patent.

Patented July 21, 1914.

Original application filed October 13, 1902, Serial No. 127,116. Divided and this application filed November 16, 1904, Serial No. 232,953. Renewed February 20, 1914. Serial No. 820,047.

To all whom it may concern:

Be it known that I, EDWARD A. STIGGINS, a citizen of the United States, residing at Beverly, in the county of Essex and Commonwealth of Massachusetts, have invented certain Improvements in Jacks for Shoe-Machines, of which the following description, in connection with the accompanying drawings, is a specification, like reference characters on the drawing indicating like parts in the several figures.

This invention relates to jacks for shoe machines and particularly to jacks for use in connection with lasting machines.

The invention is herein shown as embodied in a jack adapted especially for use in connection with the type of machine known as the "Hand Method Lasting Machine", an example of which is shown in my pending application Serial No. 127,116, filed October 13, 1902, of which this application is a division and which matured into U. S. Letters Patent No. 1,081,872 on Dec. 16, 1913.

The object of the invention is to provide an improved shoe-supporting jack by the use of which shoes can be lasted much better and with less labor than has heretofore been possible. It has become the custom to use in many grades of shoes straight counters or heel stiffeners, that is, counters which are provided with straight flange portions instead of counters which are provided with molded flanges, and to last the shoe by bending or breaking the flange portion down upon the innersole in the same operation in which the upper material is laid over the innersole. The advantage of thus breaking down the flange of each counter during the lasting operation is that the counter is thereby conformed to the particular last on which the shoe is being made, and a better fit of the shoe is obtained.

An important feature of my improved shoe-supporting jack consists in means by which the counter portion of the shoe is caused to conform accurately to the corresponding portion of the last. A difficulty which develops in breaking down the counter flanges of shoes by machines as heretofore constructed is that when the flange is bent and broken over upon the innersole the body portion of the counter is sprung away

from the counter portion of the last, and the shoe is thereby caused to bulge outwardly at this point, instead of conforming to the shape of the counter portion of the last, as it should do. To remedy this difficulty the jack of the present invention is arranged to clamp the shoe between toe and heel embracing bands, and the heel-band is so constructed that it will conform to the shape of the counter portion of the last, so that when the shoe is inserted in the jack and the heel-band is brought into position about the heel portion of the shoe, the counter is securely clamped between the band and the last and cannot spring away from the last during the breaking-down operation. The heel-band is also supported on peculiarly shaped spring arms which cause said band to embrace and clamp the sides of the heel end of the shoe and force the shoe to conform accurately to the shape of the last at the end portions of the counter.

Another feature of the new jack consists in means for preventing the formation of wrinkles in the toe portion of the shoe by the upper manipulating devices during the lasting operation. It has been found very difficult in lasting shoes made of certain kinds of leather to avoid forming fine wrinkles in the leather while stretching it with the grippers, particularly at the toe portion of the shoe. To overcome this the jack of the present invention is provided with means for wiping and stretching the upper over the whole of the toe portion of the last at the same time, and then clamping and holding the upper around said toe portion of the last until it is secured in position by the lasting and securing devices. The jack has a last-pin so mounted as to permit the last to be tipped slightly in a longitudinal direction toward the heel, and thereafter the last, coming into contact with the heel-band, is held against further longitudinal movement, and because of the binding of the last against the last-pin and the clamping of the shoe by the heel-band the last is also held against upward movement during the wiping and stretching of the upper over the toe portion of the last. The means herein shown for thus wiping and stretching the upper over the toe portion of the last is a toe-band which is arranged and

actuated to engage first with the upper on the underside of the toe portion of the inverted last and to tip the last upwardly and backwardly within the heel-band. In so doing the toe-band wipes up along the toe portion of the shoe and over the toe end of the last so as to stretch the upper, and then embraces the toe portion of the upper thus stretched around the toe of the last and holds such portion of the upper clamped in this position. The toe-band thus acts to last partially the toe portion of the shoe as it wipes the upper over the last, and thereafter to hold such portion of the shoe firmly clamped against the last. In this partially lasted condition the shoe is ready to be presented to the lasting machine to have the lasting operation completed while the upper remains clamped to the last, thus avoiding the possibility of wrinkles being formed in the toe portion of the shoe.

While the movement of the toe-band upwardly along the forwardly inclined face of the toe end of a shoe will of course force the shoe rearwardly toward and into the heel-band, this result is greatly facilitated by actuating the toe-band rearwardly as well as upwardly while it is in engagement with the toe end of the shoe, and to this end a further feature of my invention consists in imparting to the toe-band during its movement into clamping engagement with the toe end of the shoe a movement rearwardly or toward the heel-band for forcing the shoe firmly into the heel-band. As herein shown, this is effected by so connecting the toe-band to the toe-rest that after said band and rest both come into firm engagement with the shoe the toe-rest will act as a fulcrum about which the toe-band will turn upwardly and rearwardly for forcing the shoe toward the heel-band at the same time that the upper is wiped toward the bottom of the last. In the construction shown the toe-rest and toe-band are attached to a rigid carrier which is pivotally connected to an actuator shown as a post arranged for longitudinal movement only. The pivotal connection permits the carrier to rock upon the post until the rest and band have each become seated against the shoe and the shoe has moved rearwardly into the heel-band. The resistance which the yielding support for the heel-band offers to a further rearward movement of the shoe then checks the free tipping movement of the shoe, and in the further rise of the post the toe-rest becomes a fulcrum about which the carrier and toe-band turn as the band rocks upwardly and rearwardly for effecting the double purpose of wiping the upper toward the last bottom and forcing the shoe backwardly into the heel-band. The toe band and the heel band may be considered to be lasting devices because they perform lasting functions in shaping the shoe stock to

the last as will herein more fully appear. These lasting means for the opposite ends of the shoe are mounted to permit a relative movement between them for adaptation to right and left crooked lasts. The advantages of this mounting will be readily apparent. The movement is curvilinear about an axis which is located under the last between the toe and heel bands and at a substantial distance from the ends of the last. In the illustrated embodiment of the invention the toe band is the movable lasting means, its carriage being mounted to turn about a vertical axis in the longitudinally movable toe post before mentioned as supporting the carriage. The pivotal connection between the band carriage and the post is here shown as located at substantially the center of the toe band which is equivalent to the approximate center of curvature of the toe end of the last. The invention is not limited to the exact location. Preferably the toe-rest is pivotally connected to its carrier so that it may rock to seat itself squarely upon the portion of shoe engaged by it and so that in the rearward movement of the shoe it may move with the shoe, thus avoiding the friction which might otherwise be produced by the shoe sliding over the rest.

Another feature of my improved jack consists in mounting the last-pin so that it may tip transversely of the length of the jack. In some lasts the holes for the last-pin are inclined laterally and when the last is supported on a vertical pin of a jack, one side of the last bottom is higher than the other side. For the purpose of adapting the jack to support such lasts in proper position, I have movably mounted the last-pin so that it may accommodate itself automatically to the inclination of the hole made for it in the last. For the best results in overcoming the above-mentioned difficulty the last-pin should be capable of tipping about a center which is at or near its upper end, and I have therefore mounted the pin in a carrier adapted to slide in suitable guideways to give the pin the desired movement.

Another feature of the invention consists in means for adjusting the toe-band to adapt it to fit lasts which are so shaped that the bottom of the forepart is higher on one side than on the other. It is found that some lasts are so formed that the plane in which the bottom of the forepart lies is not parallel with the plane in which the bottom of the heel lies, but is inclined thereto in a direction transverse of the last; in other words, the last is twisted. When such a last is positioned properly in the jack with the heel-band flush with the innersole upon the last at both sides, the forepart of the last on one side extends above or below the plane in which the top of the toe-band is positioned, and the shoe therefore cannot be presented

properly to the lasting machine. To overcome this difficulty I have provided means for adjusting the toe-band to cause it to conform to the shape of such lasts. In the construction herein shown, this object is accomplished by movably connecting one end of the toe-band to its support, whereby that end of the toe-band can be raised above or depressed below the normal plane in which the top of the toe-band lies to position the toe-band so that its top edge will be parallel or flush with the bottom of the last all the way around the toe of the last when the toe-band is moved into operative position for embracing the toe of the last. These features of my invention and others, including certain combinations of mechanisms and details of construction, will be set forth in detail in the following specification and pointed out in the claims.

Figure 1 is a side elevation of a jack embodying the invention, a shoe being shown in the jack and presented thereby in position to be operated upon by a lasting machine. Fig. 2 is a side elevation of the jack partly in section and shows the relative positions occupied by a shoe and the several parts of the jack prior to the actuation of said parts for jacking the shoe. Fig. 3 is a similar view showing the relative positions of the several parts when the shoe has been jacked. Fig. 4 is a plan view of the jack and shows in outline the position of the toe-band and heel-band when a right shoe is clamped in the jack. Fig. 5 is a perspective view of the last-pin and its supporting means. Fig. 6 is an enlarged detail of a section on line 6—6 of Fig. 1. Fig. 7 is a vertical longitudinal sectional view through parts shown in Fig. 1. Fig. 8 is a detail showing contrasting positions, and Fig. 9 is a transverse sectional detail.

The jack comprises a base plate 1 upon which is guided the carriage 2 for supporting the toe-rest 4 and toe-band 6 and the carriage 8 for sustaining the last-pin 10 and the heel or counter-embracing band 12. The carriages are adjustable toward and from each other for shortening or lengthening the jack by a right and left threaded screw 14 which is secured against longitudinal movement in the base plate and is provided with an operating crank 16.

The heel carriage 8 has ears 18 between which is pivoted a support 20 for the last-pin 10. The lower face of the support is formed, as shown in Figs. 2 and 5, to have a limited rocking movement about its pivot and the spring plunger 24 is arranged in a socket at the rear of the pivot to rest on the carriage and hold the support and last-pin normally tipped forward. This positions the last-pin sufficiently away from the heel-band, as shown in Fig. 2, to enable the last to be readily placed upon the last-pin and

permits the pin to be rocked backwardly when the last is forced into the heel-band during the operation of jacking the shoe. The support 20 is shaped, as shown in Fig. 5, to provide two curved guideways 26 and 27 adapted to receive respectively a rib 28 and the end portion 29 of a block 30, which is formed with a socket in which the last-pin is yieldingly upheld by a spring 32. The guideways 26 and 27 are concentric, being formed upon curves which have their center at a point near the upper end of the last-pin. This construction enables the last-pin to rock transversely of the jack to compensate for any inaccuracy in the direction of the pin hole in the last. The carriage 8 is provided on either side with ears 34 to which are pivotally connected the opposite ends of a U-shaped casting 36. The casting has upwardly extending arms 38 and to these are rigidly secured springs 40 which are curved and twisted, as shown in side and end elevations in Figs. 3 and 4. The heel-band 12 is pivotally connected at its ends to the upper ends of the springs 40 and to the rear portion of the heel-band is secured the upper end of a resilient brace 42 extending downwardly to the carriage. The casting is adapted to be adjusted about its pivotal connection with the ears 34 for moving the heel-band forwardly or backwardly with relation to the last-pin by means of the screw 44 carried by the casting and adapted to bear upon the carriage.

As herein shown, the heel-band comprises an outer layer or strap *a* of strong, tough leather, an inner layer *b* of hard, firm, wear-resisting leather, and an intermediate piece *c* formed wedge-shape in cross-section and serving to shape the band so that it conforms to the vertical curvature of the heel portion of the shoe. Between the inner and outer layers and fitting closely against the upper portion of the inner layer is a strip *d* of spring metal which serves to support and give rigidity to the inner layer of hard leather and to give resiliency to the heel-band as a whole. The outer layer *a* gives the band the requisite strength and flexibility and permits of the use of a thin metallic layer *d*. A lever, comprising two parallel bars 45, is pivotally connected as herein shown to the heel-band supports 40, the outer ends of the bars being joined by a cross-piece which constitutes a handle. A yoke-shaped member 46 is connected at its ends to the lever and is adapted to extend over the heel of the shoe which has been applied to the last-pin ready to be jacked. The upper end of the yoke is provided with an adjustable contact member 47 for engaging the heel portion of the innersole of the shoe when the yoke is in its operative position. The pivotal connections between the yoke and the lever are so located that when

the lever is depressed from the position shown in Fig. 2 toward the full line position shown in Fig. 3 the shoe will be drawn downwardly against the pressure of the 5 spring sustaining the last-pin and also somewhat backwardly into the heel-band until its upper surface is flush with the upper edge of the band. The location of said pivotal connection with relation to the fulcrum 10 of the lever on the supports 40 is such that the yoke is fully depressed when the lever is in approximately its lowest position, shown in full lines in Fig. 3, and the weight of the lever and the friction of the parts will then 15 hold the shoe in this position until it is clamped between the heel-band and the toe-band. It is to be noted that this construction comprising the yieldingly supported last-pin and the depressing means constitutes a convenient arrangement by which 20 lasts differing in thickness may be positioned at the proper altitude with relation to the heel-band and will be held in such position while the operation jacking the shoe 25 is carried out.

The carriage 2 at the front of the jack is provided with a guideway extending upwardly and forwardly to receive a post 50. A carrier 52 is connected by vertical and 30 horizontal pivots to the upper end of the post, the vertical pivot being advantageously located substantially at the center of curvature of the toe portion of the last when a shoe is in the jack, as at 51 in Figs. 2 and 4, 35 and comprises a rearwardly extending arm 54 and depending outwardly inclined arms 56. The toe-rest 4 is pivotally supported upon the arm 54 and is provided with a depending finger 58 which is engaged by a 40 spring 60 secured to the carrier. The spring 60 holds the rest normally in its most advanced position, but permits it to rock rearwardly during the operation of jacking the shoe, as will be described. To the depending 45 arms 56 of the carrier 52 is attached a holder 62 which comprises three resilient arms extending upwardly in position to support the ends and middle portion of the toe-band. The band is preferably secured rigidly to the holder at its middle portion and 50 at one end, while at the other end it is connected adjustably to the holder by means which permits that end of the band to be raised or lowered with relation to the other 55 end. As herein shown, (Fig. 6) this adjustable connection comprises an eccentric bushing 64 mounted on a pivot stud 66 and received in a circular aperture in the upper end of the arm 68 of the holder. The eccentric bushing has a finger piece by means of 60 which it may be turned for raising or lowering the adjustable end of the toe-band with relation to the holder. The toe-band may thus be adjusted to position its opposite side 65 portions at different levels to locate its edges

flush with the adjacent edges of the forepart of a twisted last being jacked. The post 50 is arranged to be moved longitudinally in the carriage 2 for raising and lowering the toe-rest and toe-band, and to this end the 70 post is provided, as shown, with rack teeth which are engaged by a pinion 70 carried by a shaft 72 which is mounted in a bearing 73 formed on the side of the carriage 2. An operating handle 74 is secured to the shaft 2 75 for turning the pinion and the handle is provided with a pawl 76 adapted to engage with teeth on a circular plate 78, secured to the carriage or the shaft bearing. The handle may be locked by the pawl 76 for holding the toe-band in its elevated position. The side arms of the toe-band holder 62 are formed to hold the end portions of the band separated a distance greater than the width 80 of the widest shoe which the jack is intended to receive. When the toe-band is pressed against the toe of a last the front arm of the holder yields and the side arms are drawn inwardly to force the side portions of the toe-band into clamping contact 85 with the sides of the shoe so that the whole of the toe portion of the shoe is firmly embraced by the toe-band.

The shoe is applied to the jack with the parts, excepting the yoke 46, in the position 90 shown in Fig. 2, the last-pin tipping transversely or longitudinally of the jack to adapt itself to any inclination of the pin hole. The yoke 46 is then swung from the dotted line position shown in Fig. 3 to the 100 full line position shown in Fig. 2, and the lever 45 is moved downwardly for forcing the shoe backwardly and downwardly with relation to the heel-band until the bottom of the shoe is flush with the top of the heel-band. The operator then observes the shape 105 of the last, and if it is a twisted last having one side of the forepart higher than the other side, he relatively adjusts the two sides of the toe band vertically by means of the eccentric 64 until its edges on opposite sides of the shoe lie in a transverse plane parallel with the bottom of the last and hence when the toe band is turned into its 110 operative position they will assume a position flush with the last on both sides. The handle 74 is now depressed for moving the carrier 52 with the toe-rest and toe-band in the direction of the length of the post 50. The first effect produced by this movement 115 is to force the shoe backwardly into the heel-band, the last-pin tipping about its pivot in opposition to the spring plunger 24 as the toe-rest and toe-band become firmly seated against the forepart of the shoe. As the 120 band is closed by this movement about the last below the fuller or wider portion of the shoe and the slope of the toe end face of the last it occupies a position with its acting edge, Fig. 2, substantially parallel with the 125 130

plane of the last bottom and it maintains this relation to the plane of the last bottom while it is finally lifted to the position, Fig. 3, for wiping the upper toward lasted relation to the end and side faces of the last. 5 The carrier 52 and the toe-band then rock about the toe-rest as a fulcrum and as this fulcrum is below the acting edge of the toe-band said edge will travel upwardly and 10 backwardly and force the shoe farther rearwardly into the heel-band at the same time that it wipes the upper toward the bottom of the last. In this final movement the resilient arms of the holder 62 for the toe-band yield to permit the band to adapt itself 15 to the increasing size of the fuller portion of the last over which it is raised and to the contour of the toe end of the last.

The movable connection between the toe-rest and its support permits said rest to move with the shoe in its backward movement, thus avoiding the friction which might otherwise be produced by the shoe being compelled to slide over the rest. The backward pressure of the shoe against the middle portion of the heel-band causes the spring supporting arms 40 to yield, and because of the peculiar formation of these arms with an initial twist as shown in Fig. 4, they 25 twist farther as they yield, their inner ends moving toward the last and causing the end portions of the heel-band or counter-embracing-band to clamp the sides of the shoe at about the ends of the counter, whereby the 30 end portions of the counter are held firmly against the last. When the heel portion of the shoe has been pressed firmly into the heel-band said band, coöperating with the last-pin, prevents the forepart of the shoe 35 from being raised any higher and then the toe-band begins to ride up the toe portion of the shoe, the carrier 52 tipping about its pivotal connection with the post 50 to permit the band to rise with relation to the rest. 40 The resilient holder for the toe-band is so shaped that the sides of the band are held separated far enough to receive the widest shoe for which the band is adapted, and therefore the shoe at first is engaged by the 45 middle portion only of the band; but as the band is forced forwardly and upwardly along the toe portion of the shoe, the middle arm of the holder springs forwardly and the side arms are drawn inwardly to permit 50 the band to adapt itself to the shape and size of the toe portion of the shoe. As the band continues to rise it therefore wipes the whole toe portion of the upper toward the bottom of the last, thus precluding the forming 55 of any fine wrinkles in the upper material, and by the time the edge of the band reaches a position flush with the bottom of the last said band has firmly clamped the upper material against the toe and sides 60 of the last. It is to be noted that the toe- 65

band engages first by its middle portion with the upper on the toe portion of the last, as shown in Fig. 2, and that during the first part of the wiping movement of the band the upper is stretched in a direction longitudinal of the last. Thereafter as the band conforms to the shape of the toe portion of the last, the sides, as well as the middle portion, of the band comes into engagement with the upper, and in the final rise of the band the upper on the sides of the last also is wiped toward the bottom of the last. When this movement has been completed the parts occupy the position shown in Fig. 3 with the resilient toe-band holder and the heel-band supporting springs under tension, the toe portion of the upper and also the counter being clamped firmly against the last so that the upper can not wrinkle at the toe or the counter spring away from the last at the front ends of the counter or bulge outwardly from the heel of the last when the counter flange is broken down during the lasting operation. The pawl carried by the lever 74 will engage the ratchet teeth on the disk 78 and hold the parts of the jack in the positions to which they have been moved. The lever 45 may now be raised to release the yoke and said lever and yoke moved into the relative positions shown in dotted lines in Fig. 3, and swung downwardly where they will be out of the way. The base 1 and the described parts carried by it are supported on a post 80, Figs. 1 and 7, to which the base is connected by a cup-and-saucer joint, the cup-shaped lower face 82 of the base inclosing a plate 83 between which and the saucer-shaped head 84 of the post clamping action, fixing the base in angular relation to the post, is effected by a stem 85 and a lever 86. There is a relief spring between the head of the stem and the plate 83, and the lever is fulcrumed on the post and is operated through a rod 87 from the driving mechanism of the machine, Figs. 1 and 7, of which the jack is herein shown to be a part. 90 The jack post 80 is sustained by a lever 90 with which it has a connection permitting tipping laterally and also forwardly and backwardly between shoe receiving position and the operative position in which the shoe on the jack is presented to the machine. The lever 90 is fulcrumed on the base of the machine at 92 and its rear arm contains a socket in which the lower end of a strut 94 rests at a point near the fulcrum. The strut extends obliquely upwardly and rearwardly to a spring chamber in the machine frame where it abuts against the thimble or cap 95 of the counterbalancing spring 96, Figs. 7 and 8. The points of engagement of the strut with the spring cap 95 and with the lever 90 are so related to the fulcrum point 92 of the lever that the strut makes an increasing 100 105 110 115 120 125 130

angle with the direction in which the force of the spring is exerted as the jack is depressed, see full lines Fig. 8, whereby the jack may be stable in its depressed position. 5 As the jack is raised the spring's force is transmitted by the strut with increasing directness and effectiveness, see dotted lines Fig. 8, so that the spring will hold the jack in its upraised position. Thus the strut 10 constitutes a connection between the balancing spring 96 and the jack for causing the said spring or actuator to act with increasing force as the jack is moved to its operative position. A screw 97 provides for adjusting 15 the force of the spring 96 to balance the weight of the jack and different shoes.

The jack may be intermittently locked against angular movement on the head of its post 80 and unlocked automatically through 20 the rod 87 which is connected by a lever 100 and rod to a rack bar 102 that meshes with a pinion 103, Fig. 7, having connection through a lever 104 and rod 105 with a swinging cam arm 106, Figs. 1 and 7, that is 25 rocked by the vibrating lever 108 the upper end of which bears a roll standing in a groove in a cam block on the driving shaft of the well known lasting machine shown in Fig. 1. As the lever 108 swings toward 30 the left it rides up and engages the cam face on the swinging arm 106 and through the pinion 103 draws the rack bar 102 up, thereby drawing down upon rod 87 and plate 83 to lock the jack. During reverse movement 35 of lever 108 the rack bar is allowed to rise, as it does, under the action of a spring plunger 110 which sustains and presses upwardly against lever 104.

From Fig. 7 it may be seen that excess upward movement of the rack bar 102 after the jack has been locked against angular movement upon the head of post 80 will bodily lift the lever 100 and raise the front end of lever 90 and the entire jack. The cam face on 45 arm 106 is preferably so formed that such excess movement of the rack bar shall occur and that the jack shall be so raised unyieldingly and automatically after being clamped against angular movement on the post 80. 50 Preferably also the left hand portion of the cam face on arm 106 will be so formed as to maintain or lock the jack rigidly in upraised position for a short period before it is lowered again.

55 Preferably a Horton clutch of usual construction indicated at 111 in Fig. 1 and not necessary here to illustrate, but which is fully shown in said prior application, is interposed between the pinion 103 and the lever 104 and is arranged to be controlled by the knee lever 112. When the clutch is loose, lever 104 will be vibrated without turning the pinion 103 and when the operator closes the clutch through his control of the knee 60 lever the pinion will be oscillated for lifting

the jack intermittently, all as described more fully in said Patent No. 1,081,872.

Having thus described the preferred form of my invention and its mode of operation, I claim as new and desire to secure by Letters Patent of the United States:—

1. In a lasting machine, a jack having means movably mounted and adapted when not in use to occupy a position in the rear of and below the last bottom and to be positioned over the shoe for holding a shoe against rearward and vertical movement, a toe-band, and means for moving the toe-band to cause it to wipe the upper of the shoe along the toe portion and around the toe end of the last. 75

2. In a lasting machine, a jack comprising a toe-band, supports for said toe-band including yielding elements normally holding said band open for the insertion of the last, and means for moving the band toward the last, said yielding elements operating, when the band is brought into engagement with the last, to close said band around the toe portion of the last. 90

3. In a lasting machine, a jack having a swinging downhold, and means for actuating it into position for holding a shoe against rearward and vertical movement, combined with a toe-band having a resilient support, and means for raising the toe-band and its support to cause the band to wipe the upper yieldingly along the toe portion and over the toe end of the last. 95

4. In a lasting machine, a jack comprising a last pin for supporting a last, a toe-band, and a resilient support to which the ends of the toe-band are secured, said support holding the toe-band normally open for the convenient insertion of a last, in combination with means for moving the toe-band to cause it to wipe the upper of the shoe being lasted along the toe portion and around the toe end of the last, said resilient support being thereby put under tension to 105 cause the toe-band to clamp the sides of the toe portion of the last. 110

5. In a machine of the class described, a jack comprising means for supporting a last, and a toe-band for embracing the toe 115 end of the last, in combination with a single means for moving one side of the toe-band in the direction of the height of the last to adjust it independently of the other side and for holding it in adjusted position. 120

6. A jack, comprising a support for a shoe, a band adapted to embrace the heel portion of the shoe, and resilient supporting arms for said band extending downwardly from the front end portions of the band and 125 formed to hold the band normally open, combined with means for forcing the shoe backwardly into the band whereby the band is automatically closed about the last against the resistance of said resilient end supports. 130

7. A jack, comprising a support for a shoe, a band adapted to embrace the heel portion of the shoe, and supporting arms for said band extending downwardly from the front ends of the band and formed to yield inwardly but to resist backward pressure to a relatively greater extent, combined with means for forcing the shoe backwardly into the band whereby the band is caused to 10 clamp the shoe at the rear end and the sides of the heel.

8. In a last supporting jack, means for clamping the sides of the shoe near the ends of the counter, said means comprising 15 resilient arms, a band connecting said arms and extending around the counter, and means for producing a relative movement of the last and the band to cause the arms to clamp the end portions of the counter to the 20 last.

9. A last supporting jack comprising a base, a last pin, a heel-band, a toe-band, yielding means for supporting said bands upon the base, and means for adjusting said 25 bands toward and from each other, combined with independent means for moving one of said bands in a direction substantially perpendicular to the sole of the last to cause said bands to clamp a shoe around 30 the last at the heel and toe.

10. A jack comprising a last support, a heel-band and a toe-band, means for actuating the toe-band to cause it to force the last into the heel-band, a pivoted support for 35 said heel-band, and means for adjusting the position of said support with relation to its pivot.

11. In a lasting machine, a jack for holding a shoe, said jack comprising a counter- 40 embracing band, a rigid base, a last pin pivotally connected to said base, and yielding means for rocking said last pin about said pivotal connection to hold it normally away from said band to facilitate the application 45 of a last to the jack, combined with means for adjusting the normal distance between the pin and the band.

12. In a lasting machine, a jack provided 50 with a last pin, a last pin support mounted for tipping movement longitudinally of the jack, and a block carrying said last pin and mounted for tipping movement transversely of the jack, as and for the purpose described.

55. 13. A jack comprising means for supporting a shoe, a yieldingly supported heel-band and a toe-band, in combination with means for actuating the toe-band to force the last into the heel-band and to wipe the upper 60 into lasted position about the toe end of the last.

14. In a lasting machine, a jack for holding a shoe to be lasted, said jack comprising a movably mounted last pin arranged to 65 tip transversely of the jack and a toe-band

provided with means for adjusting one side vertically with relation to the other side, as and for the purpose described.

15. In a lasting machine, a jack for holding a shoe to be lasted, said jack comprising 70 a heel-band, a movably mounted last pin arranged to tip transversely of the jack and of the heel-band, a toe-band, and means for adjusting one side of the toe-band vertically with relation to the other side, for the 75 purpose described.

16. A jack comprising means for supporting a last, a toe-band movable into and out of operative position about the toe of the last, a flexible heel-band, and a support 80 for the heel-band, said support being constructed to cause the heel-band to clamp the last laterally when the toe-band is moved into operative position.

17. In a jack for holding a shoe to be 85 lasted, means for sustaining the shoe and means for moving the shoe rearwardly in the jack, said sustaining means comprising a toe post, means for adjusting the post vertically, a toe pad pivotally connected to 90 the post, and means for yieldingly holding the pad rocked forwardly on the post when no shoe is in the jack, whereby the pad is enabled to move in the reverse direction for accompanying the shoe in its rearward 95 movement.

18. In a jack, a movably sustained last pin, means adapted for clamping the last, and mechanism operatively connected with the clamping means for forcing the last 100 supported on said last pin downwardly into predetermined operative relation to said clamping means.

19. In a jack, means for sustaining a shoe, a toe-band having relatively movable side 105 portions, and means for actuating the band into engagement with the upper on the last and forwardly toward the toe portion of the last, said jack having provision for causing the side portions of the band to come into 110 engagement with the sides of the shoe during the latter part of said movement of the band over the upper on the toe portion of the last.

20. In a jack, a yieldingly sustained last pin, means for clamping a last which is supported on said last pin, and means operatively connected with the clamping means for forcing the last into predetermined operative relation to the clamping means and 115 maintaining it in such position until the last is clamped.

21. A jack for lasting machines, comprising means for supporting a shoe, a toe-band, a yielding support for holding the end portions of the band normally apart and out of position for engaging the sides of a shoe, and means for actuating said toe-band upwardly and forwardly whereby the upper 125 on the top of the toe portion of the last is 130

wiped forwardly by the middle portion of the band and thereafter the side portions of the band are drawn into engagement with the sides of the last and the upper on the entire toe portion of the last is wiped upwardly toward the edge of the last.

22. A jack, comprising means for holding a shoe against rearward and vertical movement including a heel-band and a member 10 relatively movable thereover to engage the shoe bottom, a toe-band arranged to yield, and means whereby said toe-band may be actuated forwardly along the toe end of a shoe and also upwardly for wiping the upper toward the bottom of the last and causing the band to clamp the upper against the last.

23. A jack, comprising means for supporting a shoe, a heel-band, and a toe-band, 20 combined with means for actuating the toe-band first upwardly into engagement with the shoe and then upwardly and rearwardly for forcing the shoe rearwardly against the heel-band.

24. A jack comprising a last pin for supporting a last, a heel-band, a toe-rest, a toe-band, and means for moving the toe-rest and the toe-band upwardly in engagement with the forepart of a shoe supported on 30 the last pin and for thereafter moving the toe-band about the toe-rest as a fulcrum upwardly and rearwardly against the shoe.

25. A jack, comprising a last pin for supporting a last, a heel-band, a carrier, a toe-rest and a toe-band mounted on said carrier, and means for actuating the carrier to move the toe-rest and toe-band into engagement with the forepart of a shoe and thereafter to move said carrier and toe-band about the toe-rest as a fulcrum for forcing the shoe rearwardly into the heel-band.

26. A jack, comprising means for supporting a shoe, a longitudinally movable post, a carrier pivotally connected to said 45 post, a toe-rest and a toe-band mounted on said carrier, and means for actuating the post to press the toe-rest and toe-band against the shoe, said pivotal connection permitting the carrier to rock about the toe-rest for swinging the toe-band upwardly and rearwardly for wiping the upper toward the shoe bottom and clamping it against the last.

27. In a jack, a heel-band, means for supporting the heel-band, and a yieldingly sustained last pin adapted to support a shoe, combined with means having connection with the heel-band support and arranged to be actuated for forcing the shoe whatever 55 its size or thickness downwardly into predetermined relation to the heel-band.

28. In a jack, a yieldingly sustained last pin adapted to support a shoe, a heel-band, and means for supporting the heel-band, combined with a lever having its fulcrum

in substantially fixed relation to said heel-band, and shoe-depressing means connected to said lever and arranged to be actuated thereby for forcing the shoe downwardly into the heel-band.

29. In a mechanism of the class described, the combination with means for sustaining a last, of lasting means, said two means being mounted for relative lateral movement between the lasting means and the last carried by said sustaining means about an axis which is substantially perpendicular to the plane of the last bottom and is located under the last at a substantial distance back of, and near the center of curvature of, the 75 adjacent end of the last.

30. In a mechanism of the class described, the combination with means for sustaining a last, of a toe-band, said two parts being mounted for relative movement laterally of 85 the toe band and the last carried by the sustaining means about an axis which is substantially perpendicular to the plane of the last bottom and is located under the last and at a substantial distance back of the toe end 90 of the last.

31. In a mechanism of the class described, the combination with means for sustaining a last, of a toe-band, said two parts being mounted for relative movement laterally of 95 the toe band and the last carried by the sustaining means about an axis which is substantially perpendicular to the plane of the last bottom and is located approximately midway between the front and the rear ends 100 of the toe-band.

32. In a shoe-supporting jack, the combination with means for sustaining the last, of bell-crank levers provided with yielding twisted arms, a heel-band connected at its 105 ends to the yielding arms of said levers, and means by which the levers may be rocked in a direction for forcing the heel-band against the end of the last whereby the twisted arms are caused to clamp the ends of the band 110 against the sides of the last.

33. In a shoe-supporting jack, the combination with means for sustaining a last, of a heel-band, and levers supporting the heel-band and comprising yielding twisted arms 115 formed and arranged to force the ends of the band against the sides of the last when the last is forced backwardly into the band.

34. In a machine of the class described, a jack comprising means for supporting a last 120 and an end lasting device formed to embrace the toe end of the last, in combination with an adjuster operatively connected with said device at one side of the jack for moving the adjacent side of said device to adjust it relatively to the other side of said device in the direction of the height of the last.

35. In a machine of the class described, means for supporting a last, an end lasting device, means for supporting said device, 125

and an eccentric operatively connecting said support and the lasting device at one side of the last for adjusting that side of the lasting device in the direction of the height of the 5 last.

36. In a machine of the class described, the combination of end lasting means, shoe supporting means including a toe rest which is restrained from bodily lateral movement, 10 a heel rest between which and the lasting means there is provision for relative curvilinear lateral movement about an axis located under the last and a substantial distance from the ends of the last and suitable 15 supporting means for said heel rest and lasting means arranged to permit the specified relative movement.

37. In a machine of the class described, the combination with a support in which a 20 last is firmly upheld and a toe lasting band arranged to be clasped about the last end a substantial distance below the plane of the last bottom and with its upper edge substantially parallel to the last bottom, of 25 means to move said band upwardly and means for maintaining such parallelism while bringing the edge of the band into substantially the plane of the last bottom.

38. A machine of the class described, having in combination, a support including toe 30 and heel parts on which a last is firmly upheld and a toe lasting device to engage the work about the last end below the fullest part of last, means connected with one side of the 35 lasting device for effecting adjusting movements of said device to position its upper edge substantially parallel with the last bottom, and means to move said device relatively to the last support toward the plane 40 of the shoe bottom past said full part of the last, said machine having provision for permitting expansion of said device throughout its length in passing said full part of the last.

45. 39. In a lasting machine, toe embracing lasting means, means for operating the same to wipe the upper toward lasted relation to the shoe bottom, and adjusting means arranged for convenient manipulation in connection with each shoe being lasted to move 50 one side of said lasting means perpendicularly to the plane of the last bottom and relatively to a substantially fixed supporting connection for the other side of said 55 lasting means.

40. In a machine of the class described, a jack for holding a shoe, and mechanism for balancing the jack when in an upraised position, said mechanism including an actuator 60 and a strut arranged to make an increasing angle with the direction of the force ex-

erted by the actuator as the jack is depressed, whereby the jack may be stable in its depressed position.

41. In a machine of the class described, a 65 jack for holding a shoe, a spring for raising the jack into an operative position, and connections between the spring and the jack for causing the spring to act with increasing force on the jack as the jack is moved 70 toward its operative position.

42. In a machine of the class described, a shoe bottom rest, a jack for holding a shoe, and mechanism for forcing the jack upward toward the shoe rest, said mechanism comprising a lever, a spring, and a connecting device between said lever and spring arranged to apply the force of the spring to the lever with increasing directness as the 75 jack is moved toward the shoe rest. 80

43. In a lasting machine, a jack for holding a shoe, means for sustaining the jack to hold the shoe in position to be operated upon, and means under the control of the operator for lifting the jack. 85

44. In a lasting machine, a jack, a support therefor, a movable connection between the jack and its support, and means for automatically locking the jack upon its support and raising the jack. 90

45. In a lasting machine, the combination with a jack, a support on which the jack rests for angular movement, and means connecting the jack to its support, of means for automatically actuating said connecting 95 means to lock the jack and unlock it intermittently.

46. In a lasting machine, the combination with a jack and a support therefor, of a movable connection between the jack and its support for the purpose described, and means for automatically locking the jack upon its support and for automatically raising the jack and support and locking them in raised position. 100 105

47. In a lasting machine, the combination with a jack and a support therefor, of means for yieldingly sustaining the jack, a movable connection between the jack and its support for the purpose described, and 110 means for automatically locking the jack on its support and for positively raising the jack and rigidly sustaining it in raised position.

In testimony whereof I have signed my name to the specification in the presence of two subscribing witnesses.

EDWARD A. STIGGINS.
